(57) **CLAIM**

The ornamental design for a “spraying device for bottles,” as shown.

DESCRIPTION

FIG. 1 is a side lateral view of the spraying device for bottles; FIG. 2 is a front view of the spraying device for bottles; FIG. 3 is a side lateral view opposite to that of FIG. 1; FIG. 4 is a rear view of the spraying device for bottles; FIG. 5 is a top view of the spraying device for bottles; FIG. 6 is a bottom plan view of the spraying device for bottles; and, FIG. 7 is a perspective view of the spraying device for bottles. The broken lines in the figures depict portions of the spraying device that form no part of the claimed design.
